Primary Examiner—Holly H. Baynham*Assistant Examiner*—Sheryl Friedman*(74) Attorney, Agent, or Firm*—Dennis A. Gross; The Hill Firm(57) **CLAIM**

I claim as my invention the ornamental design for a ground anchor, as shown and described.

DESCRIPTION

FIG. 1 is a side elevational view of a ground anchor according to this invention.

FIG. 2 is a top plan view of the anchor of FIG. 1.

FIG. 3 is an end plan view of the ground anchor of FIG. 1 taken from the bottom of FIG. 1.

FIG. 4 is a side elevational view similar to FIG. 1 showing the opposite side of the ground anchor from FIG. 1.

FIG. 5 is a bottom plan view of the anchor of FIG. 1 showing the bottom side opposite the side shown in FIG. 2; and,

FIG. 6 is a back end plan view of the anchor of FIG. 1 shown from the top of FIG. 1.
